HYDROCARBON CONVERSION

Roland B. Day and Elmer R. Kanhofer, Chicago,
Ill., assignors to Universal Oil Products Com-
pany, Chicago, Ill., a corporation of Delaware

Application July 26, 1940, Serial No. 347,756

2 Claims. (Cl. 196—52)

This invention relates to a process for the production of high yields of high octane rating gasoline and more specifically to a process involving both thermal and catalytic treatments whereby the hydrocarbon oil to be converted is treated under optimum conditions for conversion to high octane rating gasoline.

Catalytic cracking as ordinarily conducted does not employ recycling of insufficiently converted products to the conversion zone because, as has been found, such insufficiently converted hydrocarbons contain a high percentage of aromatics, cyclo-olefins, cyclo-diolefins, and diolefin hydrocarbon compounds, the tendency of which is to deposit great amounts of carbon or carbonaceous substances upon the catalyst particles, if recycled to the catalyst zone, resulting in a more rapid lowering of catalyst activity than is encountered when passing clean unconverted oils in contact with such catalysts. In order to reduce the formation of carbonaceous substances during conversion, resulting in shorter reactivation times and lower peak reactivating temperatures, it is usual to pass the hydrocarbon oil in contact with the catalyst only once and then thermally crack the insufficiently converted oils in a thermal cracking system. In a process employing both thermal and catalytic cracking in the manner above mentioned, the yield and octane of the gasoline product are good but not as good as one might expect from a process wherein the catalytic recycle is also catalytically cracked.

In our invention involving both catalytic and thermal treatments the two steps have been combined in a novel and advantageous manner so that a relatively large proportion of the insufficiently converted hydrocarbons from the catalytic treatment are subjected to thermal treatment under conditions which favor the removal of the carbon forming constituents from the insufficiently converted hydrocarbons rather than thermal cracking to gasoline, although some thermal cracking may occur. By this method compounds undesirable in catalytic cracking, because of their tendency to form carbon, such as, for example, diolefins, aromatics, cyclo-olefins, and cyclodiolefins are probably polymerized or undergo some treatment which converts them to higher boiling hydrocarbons which are removed as residue from the thermal treating system.

In one specific embodiment the invention comprises subjecting a relatively heavy hydrocarbon oil to thermal treatment under viscosity breaking conditions in a heating coil and communicating reaction chamber, commingling the conver-

sion products with reaction products formed in the thermal treatment and light and heavy reflux condensates as hereinafter set forth and separating the mixture into non-vaporous liquid residue and vaporous reaction products, recovering the former, fractionating said vaporous reaction products, together with catalytic conversion products formed as hereinafter set forth to separate fractionated vapors boiling substantially in the range of gasoline from the higher boiling hydrocarbons, recovering the former, condensing said higher boiling hydrocarbons as light and heavy reflux condensates in the fractionating zone, commingling a portion of said light reflux condensate with a relatively light hydrocarbon oil, heating and vaporizing the mixture and passing the heated vapors in contact with a cracking catalyst, fractionating the catalytic conversion products as hereinbefore set forth, subjecting the residual portion of said light reflux condensate to thermal treatment, simultaneously therewith subjecting said heavy reflux condensate to a separate thermal treatment, commingling the resulting reaction products from the thermal treatments of both reflux condensates with the conversion products formed in the thermal treatment of said heavy oil for treatment as hereinbefore set forth.

The primary object of this invention is to provide a combination of thermal and catalytic cracking wherein provisions are made for handling heavy distillation residues, such as, for example, topped or reduced crude oils and at the same time provide for thermally treating the insufficiently converted hydrocarbons from the catalytic cracking step to effect a removal of undesirable carbon forming constituents contained in the catalytic conversion products, since these materials if returned to the catalytic conversion step would result in the formation of large amounts of carbonaceous substances which deposit upon the catalytic material and lower the activity thereof.

The object of the invention may be accomplished in the following manner. Heavy charging oil comprising, for example, topped or reduced crude oil is subjected to thermal viscosity breaking conditions in a heating coil and communicating reaction chamber. Reaction products formed in the thermal treatment of light and heavy reflux condensates in the manner to be described may be commingled with the reaction products formed in the thermal treatment of the heavy oil before or after introduction of the latter to the reaction chamber. The resulting mixture of re-

action products is supplied to a vaporizing and separating chamber wherein non-vaporous liquid residue is separated from the vaporous reaction products and the former recovered. The vaporous reaction products are commingled with catalytic conversion products formed in a subsequent step of the process and the mixture fractionated to separate gasoline boiling range hydrocarbons from the heavier hydrocarbons. The heavier hydrocarbons condensed in the fractionating zone are further separated therein into light and heavy reflux condensates. A portion of the light reflux condensate may be subjected to catalytic treatment above but preferably is commingled with a light oil charging stock comprising, for example, naphtha, kerosene, or gas oil, the mixture heated and vaporized, and the resulting vapors passed in contact with a mass of cracking catalyst. The catalytic conversion products formed in this treatment are subjected to fractionation in the manner previously described. The heavy reflux condensate is subjected to thermal treatment in a heating coil and, as above mentioned, may be introduced to the reaction chamber or commingled with the stream of conversion products leaving the reaction chamber while the residual portion of the light reflux condensate may be subjected to a separate thermal treatment and the resulting conversion products commingled with the conversion products in the reaction chamber or with those leaving the reaction chamber or, when desired, the residual portion of light reflux condensate may be commingled with the heavy reflux condensate and this mixture subjected to thermal treatment.

In the preferred embodiment of the invention a relatively larger portion of the insufficiently converted hydrocarbons formed in both the catalytic and thermal treatments is returned to the thermal treatment as compared to the portion supplied to the catalytic treatment, although in some cases substantially equal amounts may be supplied to each step. By selecting conditions in the thermal treatment, which will permit operating in this manner, theoretically the insufficiently converted hydrocarbons make at least one pass through the thermal treating step before being subjected to cracking in the presence of catalytic material. In one or more passes of the insufficiently converted hydrocarbons through the thermal treating step, the undesirable carbon forming constituents which are formed in catalytic cracking are removed and recovered as non-vaporous liquid residue, whereas if these materials were returned to catalytic cracking a heavy deposition of carbonaceous substances on the catalytic material would result.

The accompanying diagrammatic drawing illustrates in conventional side elevation one specific form of the apparatus which may be employed to accomplish the objects of the invention.

Referring to the drawing, heavy charging oil comprising, for example, a topped or reduced crude oil, is introduced through line 1 containing valve 2 to pump 3 which discharges through line 4 containing valve 5 into heating coil 6. The oil in passing through heating coil 6 is raised to a viscosity breaking temperature ranging, for example, from 800 to 1000° F., or thereabouts, by means of heat supplied from furnace 7, preferably while maintaining the oil under a superatmospheric pressure ranging, for example, from 100 to 600 pounds or more per square inch. The heated reaction products leaving heating coil 6 are directed through line 8 containing valve 9

into reaction chamber 10. In the case here illustrated, other reaction products formed in the manner to be described may be supplied to reaction chamber 10 and commingled therein with the reaction products introduced as above mentioned wherein substantial further conversion results. Reaction chamber 10, in the case here illustrated, is preferably operated at a superatmospheric pressure of approximately the same order or slightly less than that employed in the heating coils from which the reaction products are derived and is preferably insulated to reduce radiation losses therefrom, although no insulation appears in the drawing.

Reaction products leaving chamber 10 are directed through line 11 containing valve 12 and, when desired, may be commingled with reaction products formed in the manner to be described, which are not introduced to chamber 10, and the resulting mixture thereafter introduced to vaporizing and separating chamber 13. Chamber 13, in the case here illustrated, is preferably operated at a substantially reduced pressure relative to that employed in chamber 10, being of the order of 50 to 200 pounds or more per square inch. Vaporous and liquid reaction products are substantially separated in chamber 13 and the latter substantially further vaporized to form a non-vaporous liquid residue which is removed therefrom by way of line 14 containing valve 15, and recovered as a product of the process or subjected to any desired further treatment.

Vaporous reaction products leaving chamber 13, including vapors evolved therein, are directed through line 16 containing valve 17, commingled with catalytic conversion products formed in the manner to be described, and the mixture introduced to fractionator 18. Fractionator 18, together with the condensing and collecting equipment in communication therewith, may be operated at a pressure of substantially the same order as that employed in chamber 13, but in case lower pressures are employed in the catalytic conversion zone fractionator 18 may be operated at a pressure comparable therewith. Vaporous reaction products and catalytic conversion products are fractionated in fractionator 18 to separate fractionated vapors boiling substantially in the range of gasoline from the higher boiling insufficiently converted hydrocarbons.

Fractionated vapors separated in fractionator 18 are conducted through line 19 containing valve 20 to cooling and condensation in condenser 21. The distillate, together with undissolved and uncondensed gases in condenser 21, is directed through line 22 containing valve 23 into receiver 24 wherein the distillate and gases are collected and separated. Undissolved and uncondensed gases collected and separated in receiver 24 are removed therefrom by way of line 25 containing valve 26, recovered as a product of the process or subjected to any desired further treatment. A portion of the distillate collected and separated in receiver 24 is returned to the upper portion of fractionator 18 by well known means, not shown, to serve as a refluxing and cooling medium and the residual portion thereof is removed from receiver 24 by way of line 27 containing valve 28, recovered as a product of the process or subjected to any desired further treatment.

The heavy insufficiently converted hydrocarbons separated in fractionator 18 are condensed therein into light and heavy reflux condensates, the lighter reflux condensate preferably comprising hydrocarbons boiling below 600° F. while the

heavy reflux condensate includes those hydrocarbons boiling above 600° F. Light reflux condensate separated in fractionator 18 is directed through line 29 containing valve 30 to pump 31. Pump 31 discharges through line 32 and all of the light reflux condensate may be directed through valve 33 into line 37 and thereafter subjected to catalytic cracking in the manner to be described. Preferably, however, only a portion of the light reflux condensate in line 32 is directed through valve 33 to catalytic cracking while the residual portion thereof is subjected to thermal treatment in the manner to be described. The light reflux condensate supplied to line 37 by way of line 32 may be introduced to heating coil 39 alone, however, in some cases, it may be commingled with a relatively light hydrocarbon oil, such as, for example, gas oil, naphtha, or kerosene introduced from an exterior source by way of line 34, valve 35, pump 36, line 37 and valve 38 and the mixture supplied to heating coil 39. When desired, steam and/or light gaseous products, the latter comprising either those formed in the process or light gases introduced from an exterior source, are commingled with the hydrocarbon oil in line 37 to aid in substantially completely vaporizing said hydrocarbon oil and also as a means for reducing the total pressure on said oil. Heating coil 39 receives heat from furnace 40 whereby the oil introduced thereto is substantially completely vaporized and heated to a temperature ranging, for example, from 800 to 1200° F. preferably while maintaining said oil at a pressure ranging, for example, from substantially atmospheric to 200 pounds or more per square inch.

The heated reactants leaving coil 39 are directed through line 41 containing valve 42 into reactor 43 which contains catalytic material capable of effecting the desired conversion reaction. In the case here illustrated, reactor 43 may comprise, for example, a zone of the heat exchanger type wherein the catalyst is contained in a plurality of elongated tubular elements of relatively small diameter and wherein provisions are made for passing some suitable heat convective medium such as combustion gases in contact with the exterior of said elongated tubular elements whereby to supply heat to the reactants during conversion and to effect cooling during reactivation of the mass of catalytic material. Reactor 43, on the other hand, may comprise a cylindrical vessel which is well insulated to reduce radiation losses and which contains one or a plurality of beds of catalytic material wherein the reaction may be accomplished substantially adiabatically.

In the catalytic cracking of hydrocarbons relatively large amounts of carbonaceous substances are formed which deposit upon the catalytic material thereby reducing its active surface and necessitating reactivation at periodic frequent intervals. The invention contemplates reactivating the used catalytic material in the usual manner, such as, for example, by passing oxygen-containing reactivating gases in contact with the used catalytic material and removing carbonaceous substances as combustion gases along with the spent reactivating gases. It is desirable therefore, in order that the operation may be carried out as a continuous process to employ at least two reactors, and in some instances more than two reactors, so that while the catalytic material in one reactor is being used for effecting conversion of the hydrocarbon reactants the catalytic material in the other or others may be undergoing reactivation.

Catalysts which have been found to be effective in the catalytic cracking of hydrocarbon vapors may comprise pellets or granules of silica or other siliceous and refractory materials composed with compounds selected from the group consisting of alumina, zirconia, and thoria. In addition, the hydrosilicates of alumina, acid treated clays, or the like, have also been found to be effective in the cracking treatment of hydrocarbon vapors. Although the catalysts above recited are generally considered to be the preferred catalysts their use is not to be construed as a limiting feature, for various other catalysts well known to those in the art may be employed within the broad scope of the invention.

Conversion products leaving reactor 43 are directed through line 44 containing valve 45 into line 46, commingling therein with the vaporous reaction products formed in the manner previously described, and the mixture supplied to fractionator 18 in the manner previously described.

The residual portion of the light reflux condensate in line 32 may be directed through line 46 containing valve 47 into line 59 where it commingles with the heavy reflux condensate for treatment in the manner to be described. Preferably, however, the remaining light reflux condensate in line 32 is subjected to a separate thermal treatment which is accomplished by directing the same through line 48 containing valve 49 to pump 50. Pump 50 discharges through line 51 containing valve 52 into heating coil 53 which receives heat from furnace 54. Preferably also, in order that substantially all of the insufficiently converted hydrocarbons formed in both the thermal and catalytic treatments may be subjected to some thermal treatment, the quantity of insufficiently converted hydrocarbons including both light and heavy reflux condensates returned to the thermal treatment should be equal to, if not greater than, the amount of light reflux condensate directed through valve 33 in line 32 for catalytic cracking in the manner previously described.

Light reflux condensate passing through coil 53 is subjected to conditions of temperature and pressure favorable to the conversion of the undesirable compounds present therein which are bad carbon formers when brought in contact with the catalytic materials whereby these materials are converted into heavier hydrocarbons and subsequently removed as liquid residue in vaporizing and separating chamber 13. Temperatures to which the light reflux condensate may be heated in coil 53 may range from 800 to 1000° F., or thereabouts, while employing a superatmospheric pressure ranging, for example, from 100 to 1000 pounds or more per square inch. The heated products leaving coil 53 by way of line 55 may be directed through valve 56 into line 66 wherein they may commingle with the reaction products from the thermal cracking of the heavy reflux condensate formed in the manner to be described and the mixture introduced to chamber 10. In another manner of operation the reaction products leaving coil 53 by way of line 55 may be directed through line 57 containing valve 58 into line 68 by means of which they are supplied to line 11, commingling therein with the reaction products leaving chamber 10 for treatment in the manner previously described.

Heavy reflux condensate leaving fractionator 18 is directed through line 59 containing valve 60 to pump 61 or when desired, the heavy reflux

condensate in line 59 may be commingled with the light reflux condensate supplied thereto by way of line 46 in the manner previously described and the mixture supplied to pump 61. Pump 61 discharges through line 62 containing valve 63 into heating coil 64 which receives heat from furnace 65. The oil in passing through coil 64 is raised to a thermal cracking temperature ranging, for example, from 800 to 1050° F., or thereabouts, while being maintained at a superatmospheric pressure ranging from 100 to 600 pounds or more per square inch. The reaction products leaving coil 64 by way of line 66 may be directed through valve 67 into reaction chamber 10 for treatment in the manner previously described or they may be directed through line 68 containing valve 69 into line 11 where they commingle with the reaction products leaving chamber 10.

An example of one specific operation of the process as it may be accomplished in an apparatus such as illustrated and above described is approximately as follows: Heavy charging oil comprising a 25° A. P. I. gravity Mid-Continent reduced crude oil is heated to a temperature of 890° F. while employing a pressure of 200 pounds per square inch on the outlet of the heating coil. The reaction products formed in the heating coil are commingled with other reaction products formed by the thermal treatment of light and heavy reflux condensates in the manner to be described and the mixture introduced to a reaction chamber operated at a superatmospheric pressure of 200 pounds per square inch.

The reaction products leaving the reaction chamber are supplied to a vaporizing and separating chamber operated at a superatmospheric pressure of 40 pounds per square inch wherein vaporous reaction products are separated from the non-vaporous liquid residue formed in the operation and the latter recovered as a product of the process. Vaporous reaction products separated as above mentioned are commingled with catalytic conversion products formed in the manner to be described and the mixture fractionated at a superatmospheric pressure of approximately 40 pounds per square inch to separate vapors of approximately 400 end point from the higher boiling insufficiently converted hydrocarbons. The vapors separated as above mentioned are subjected to cooling and condensation and the resulting distillate and gas collected and separated.

The higher boiling insufficiently converted hydrocarbons are condensed as reflux condensate in the fractionator and the total reflux condensate substantially further separated into light reflux condensate of approximately 550° F. end point and heavy reflux condensate which includes all of the hydrocarbons boiling above 550° F. Approximately one-half of the light reflux condensate separated as above mentioned is commingled with an equal volume of 33° A. P. I. gravity Mid-Continent gas oil and the mixture heated and vaporized at a temperature of 980° F. and at a pressure of 45 pounds per square inch. The heated vapors are passed in contact with a mass of synthetically prepared silica-alumina catalyst at a liquid hourly space velocity of approximately 2 and the catalytic conversion products formed are fractionated in the manner previously described.

The residual portion of the light reflux condensate not subjected to catalytic cracking is treated thermally at a temperature of approximately 850° F. and under a superatmospheric pressure of approximately 300 pounds per square inch. The reaction products formed by this thermal treatment are commingled with other reaction products in the reaction chamber as above mentioned.

Heavy reflux condensate separated as above mentioned is subjected to thermal treatment in a heating coil at a temperature of 920° F. while maintaining the oil under a superatmospheric pressure of 400 pounds per square inch. The reaction products leaving the heating coil are commingled with the reaction products formed in the thermal treatments of the charging stock and the light reflux condensate and the mixture subjected to prolonged treatment in the reaction chamber as above mentioned.

From an operation employing conditions as above described one may obtain approximately 64.0% of 400° F. end point gasoline of approximately 75.5 octane number, 23.0% of non-vaporous liquid residue at approximately 10° F. A. P. I. gravity, the balance being principally carbon, gas, and loss.

We claim as our invention:

1. A process for the conversion of hydrocarbon oil, which comprises thermally cracking a relatively heavy oil, catalytically cracking a relatively light oil, combining cracked vapors from both cracking steps and fractionating the same to form light and heavy reflux condensate, recovering the fractionated vapors, supplying a regulated quantity of said light reflux condensate to the catalytic cracking step, subjecting another quantity of said light reflux condensate and said heavy reflux condensate to thermal cracking independently of said relatively heavy oil and independently of each other to form cracked vapors and to convert undesirable carbon forming constituents into liquid residue, separating liquid residue from the cracked vapors, and supplying the last mentioned cracked vapors to the fractionating step.

2. A process for the conversion of hydrocarbon oil which comprises thermally cracking a relatively heavy hydrocarbon oil to form cracked vapors having a lower average boiling point than said oil, separating liquid residue from said cracked vapors, fractionating the latter to form light and heavy reflux condensates, recovering the fractionated vapors, dividing the light reflux condensate into at least three portions of like composition, subjecting one of said portions to catalytic cracking, supplying resulting conversion products to the fractionating step, combining another of said portions with said heavy reflux condensate and subjecting the mixture to thermal cracking, independently of said heavy oil and subjecting still another of said portions to thermal cracking independently of said heavy oil and of said mixture, to form cracked vapors and to convert undesirable carbon forming materials into liquid residue, separating the last named liquid residue from the last mentioned cracked vapors, and supplying the latter to the fractionating step.
